DESIGN FOR A ROTARY MOWER HOUSING

William H. Huff, Kansas City, Mo.

Application May 23, 1947, Serial No. 139,221

Term of patent 7 years

(Cl. D40—1)

To all whom it may concern:

Be it known that I, William H. Huff, a citizen of the United States, residing at Kansas City, in the county of Wyandotte and State of Kansas, have invented a new, original, and ornamental Design for a Rotary Mower Housing, of which the following is a specification, reference being had to the accompanying drawing, forming part thereof, in which

Fig. 1 of the drawing is a plan view of a rotary mower housing, showing my new design,

Fig. 2 is a side elevational view of the rotary mower housing, and

Fig. 3 is a front elevational view of the rotary mower housing.

I claim:

The ornamental design for a rotary mower housing, substantially as shown.

WILLIAM H. HUFF.
